Filed May 22, 1973, Ser. No. 362,790

Term of patent 14 years

Int. Cl. D12—11

U.S. Cl. D12—107

The figure is a perspective view of a combined velocipede and carrier showing my new design, it being understood that the opposite side is a mirror image of the side shown while the rear panel of the carrier is plain and unornamented.

I claim:

The ornamental design for a combined velocipede and carrier, as shown and described.
